UNITED STATES PATENT OFFICE.

LAMBERT SCHMIDT, OF BROOKLYN, NEW YORK, ASSIGNOR TO RADIOTIVE CORPORATION, OF BROOKLYN, NEW YORK, A CORPORATION OF NEW YORK.

TELEPHONE APPARATUS.

Application filed June 26, 1922. Serial No. 570,869.

To all whom it may concern:

Be it known that I, LAMBERT SCHMIDT, a citizen of the United States, and a resident of the borough of Brooklyn, county of Kings, city and State of New York, have invented certain new and useful Improvements in Telephone Apparatus, of which the following is a specification.

This invention relates to telephone apparatus and more particularly, to a loud speaking receiver for use in connection with apparatus employed for the purpose of establishing wireless telephonic communication.

Generically considered, it is the primary object and purpose of my present invention to provide a receiver of the magnet type which will be highly sensitive and instantly responsive to the slightest variations in polarity of the alternating currents coming in over the line.

More particularly, my invention comprehends a radically new form and construction of the armature having a resiliently balanced suspension in the bore of the translating coil spool. This armature, in the preferred embodiment of the invention, is of cylindrical form and the pole shoes of the permanent magnet are so related to the ends of the armature at opposite sides thereof that the magnetic flux acting over a relatively small area produces an instantaneous responsive movement of the armature to the slightest pulsations of the alternating currents passing through the translating coil.

As a detail item of improvement in instruments of this character, I provide a two-part armature and fulcrum means therefor which is secured and held in assembled relation with the armature parts when the latter are connected so that the armature and its fulcrum in fact, constitute a single unit and capable of assemblage in operative position by the mere insertion of the armature through the bore of the coil spool.

In general, my present improvements provide a telephone receiver as above characterized, which, though highly sensitive in its action, is nevertheless composed of simply and substantially constructed elements which are capable of operative association in very compact relation and may be confined within a casing of appreciably smaller size than it is possible to use in instruments

of this character as heretofore constructed.

With the above and other objects in view, the invention consists in the improved telephone receiver and in the form, construction and relative arrangement of its several parts as will be hereinafter more fully described, illustrated in the accompanying drawings and subsequently incorporated in the subjoined claims.

In the drawing wherein I have illustrated one desirable and practical embodiment of the invention and in which similar reference characters designate corresponding parts throughout the several views,

Figure 1 is a rear elevation, the casing being removed to illustrate one embodiment of my improved telephone receiver;

Figure 2 is a section taken on the line 2—2 of Figure 1;

Figure 3 is a view looking in a direction at right angles to Figure 1;

Figure 4 is an enlarged detail section taken on the line 4—4 of Figure 3, and

Figure 5 is a perspective view showing the several parts of the armature and its fulcrum in separated relation.

In the embodiment of my invention which I have selected for purposes of illustration, there is provided a permanent magnet 5 of the conventional U-shaped form. To the inner opposed faces of the parallel legs of this permanent magnet the pole pieces 6 and 7 respectively, are suitably secured, as by means of the screws 8. These pole pieces at their relatively opposite ends are formed with flanges 9 and 10 respectively, projecting inwardly from the attached arms of said pole pieces. Each flange is provided at its ends with the angularly disposed shoes 11 and 12 respectively, the shoes of each pole piece projecting towards the shoes on the other pole piece and the opposed shoes being positioned in the same plane.

The pole shoes 11 and 12 embrace the cylindrical spool 13, which is of a suitable non-magnetic material, of the cylindrical translating coil 14. The spool 13 has the usual cylindrical bore 15 open at its opposite ends.

One edge of the permanent magnet 5 is engaged against the inner face of a front plate 16 also of a suitable non-magnetic material and to this plate the angular portion 9 of the pole piece 6 is securely riveted or otherwise fixed.

The armature as herein shown, comprises two complementary cylindrical sections 17 and 18 respectively. These armature sections have a maximum diameter somewhat less than the diameter of the bore 15 of the coil spool. Each armature section has one end portion gradually reduced in diameter inwardly to its approximate center to thereby provide a tapering portion 19. The armature section 17 at the end of its tapering portion is formed with an axially projecting threaded stud 20 adapted for engagement in a complementary threaded bore formed in the tapered end portion of the other armature section 18.

The fulcrum for the armature consists of two similar sheet metal parts 21, each of said parts having a sleeve 22 longitudinally split on one side as at 23. At one end of the intermediate portion of the sleeve an ear 24 is disposed at right angles to the axis of the sleeve and in opposed relation to the end thereof, the spaced parts of the sleeve being obliquely cut from the split 23 to the juncture of the ear 24 with the sleeve body, as indicated at 25. Each ear 24 has a central aperture 26 to receive the threaded stud 20. The split sleeve of each fulcrum member embraces the tapering portion 19 of each armature section adjacent its inner smaller end. These sleeves are of greater external diameter than the maximum diameter of the armature sections so that they will have a frictional snug fit against the wall of the bore in the coil spool. The inner diameters of the sleeves are also slightly greater than the diameters of the tapering portions of the armature sections around which they are engaged. Thus it will be understood that when the armature is inserted through the bore of the coil spool, it is supported in its normal position in coinciding axial relation with the spool bore solely by means of the ears 24.

The opposite ends of the two-part armature project beyond the spool bore and are disposed between the complementary opposed shoes of the pole pieces 6 and 7. The end faces of the pole shoes are concave, as indicated at 27, and are slightly eccentric with relation to the cylindrical armature so that in the normal position of the armature, the ends of these concave faces are somewhat nearer to the periphery of the armature than the central portion thereof. Greater responsiveness of the armature to variations in the magnetic flux is thus produced since the lines of magnetic force are concentrated and more equally distributed in radial directions with respect to the cylindrical armature.

The end of the armature projecting from the inner end of the spool bore is provided with a reduced portion having a transverse groove 28 in one side thereof to receive a

head 30 provided upon one end of a wire rod 29 which extends loosely through an opening in the end of the armature. There is thus provided a swivel connection between the rod 29 and the end of the armature so that said rod will always remain in a perpendicular position relative to the front plate 16 in the arcuate movement of the armature end between the pole shoes. Preferably, I provide a split sleeve 30' which is adapted to be engaged over the reduced end of the armature to protect the pivotal connection with the rod 29 so that free pivotal action is assured. The rod 29 extends through a central opening in the plate 16 and is suitably connected to a non-magnetic disc 31 which may be of mica or other suitable material, and is engaged at its marginal edge upon an annular rib 32 formed upon the outer side of the plate 16.

It will be understood that suitable binding posts are mounted on the front plate 16 and insulated from each other to which the ends of the electromagnetic coil and the wires of the telephonic receiving circuit are respectively connected.

The magnetic structure above described is enclosed within a casing 33 of hard rubber or other suitable material which is exteriorly threaded at one end to receive the usual ear piece 34 having the central opening therein through which the sounds caused by vibrations of the diaphragm 31 are disseminated.

In the operation of the telephone instrument above described, it will be understood that the alternating currents coming in over the line are translated by the electromagnetic coil and as long as the magnetic flux of the pole pieces is equal, the cylindrical armature will remain in a normal position in coinciding axial relation to the bore of the coil spool. The passage of fluctuating voice currents over the receiving circuit causes changes in direction and strength of the magnetic flux in accordance with the variations in the voice currents and thus produces a corresponding variation in the attraction and repulsion of the armature relative to the pole shoes. The fulcrum members are preferably produced from finely tempered steel of such gauge that the armature will instantly respond to the slightest variations in polarity of the alternating current. The two ears 24 being closely engaged with each other constitute in effect a single fulcrum support for the armature, the point of fulcrum being located at the juncture of these ears with the sleeve members. The armature may thus vibrate without restraint in the spool bore, such vibrations being transmitted through the medium of the pivotally connected rod to the flexible diaphragm which produces sounds at the ear piece corresponding to the telephonic currents traversing the translating coil. As

the fulcrum members are rigidly secured to the cylindrical armature at its axial center, no binding action is possible, the actual fulcrum point of the armature being entirely 5 free from frictional influences and thus materially increasing the responsiveness of the armature to minute changes in the fluctuating voice currents.

I have found in practice that by providing a fulcrum means for the armature as above described and eliminating the separate and independent armature support secured to the pole shoes as heretofore used, the armature may be employed in connection 10 with the familiar cylindrical magnetic coil which is less expensive and may be more easily wound than the oval or elongated type of coil. Also, it will be apparent that by reason of the very simple and compact 15 mounting and arrangement of the magnetic coil and the armature as herein disclosed, it is possible to house or enclose the magnetic construction within a casing of unusually 20 small dimensions.

While primarily the present invention is 25 designed for use as a telephone receiver, it is obvious that the instrument might also be used as a transmitter, since when the sound waves of the voice are impressed upon the 30 diaphragm the vibration of the latter causes a movement of the armature. This produces electrical impulses in the coil which will be transmitted over the line. Also, I have herein referred to the universal pivotal connection 35 between the rod 29 and the end of the cylindrical armature. This feature is not, however, claimed in detail as it forms the subject matter of a separate application for 40 patent filed of even date herewith. In the present application, however, I shall claim this connection with the diaphragm only in a broad sense in conjunction with the armature mounting.

The several other structural features of 45 my improvement as above explained are likewise susceptible of embodiment in other alternative structures and I accordingly reserve the privilege of adopting all such legitimate modifications in the form, construction and relative arrangement of the 50 several parts which may be fairly considered as within the spirit and scope of the invention as claimed.

I claim:

1. In telephonic apparatus, a magnet coil, 55 an armature extending through the bore of said coil and an automatically balanced suspension means for the armature having a part stationary with respect to the armature and frictionally engaged with the surface of the coil bore, said means normally maintaining the armature in coinciding axial relation with the coil.

2. In telephonic apparatus, a magnet coil, 60 an armature adapted to be positioned

through said coil, and resilient fulcrum means carried by the armature to coact with the wall of the coil bore and maintain the armature in automatically balanced suspension in said bore in coinciding axial relation 70 therewith.

3. In telephonic apparatus, a cylindrical magnet coil and its spool, a cylindrical armature adapted to be positioned through the spool bore, and resilient fulcrum means carried by the armature and coacting with the wall of the spool bore to automatically maintain the cylindrical armature in balanced suspension with its axis in coinciding relation with the axis of the spool. 75

4. In telephonic apparatus, a cylindrical magnet coil, a cylindrical armature enclosed by said coil, and resilient fulcrum means for the armature automatically acting to maintain the armature in balanced suspension in 80 coinciding axial relation with the axis of said coil, said fulcrum means having a part stationary with respect to the armature and removably engaged with the magnet coil.

5. In telephonic apparatus, a magnet coil, 85 a cylindrical armature enclosed by said coil, and resilient fulcrum means carried by the armature and having parts in frictional bearing contact with the bore of said coil, said fulcrum means maintaining the cylindrical armature in balanced suspension within the coil and in coinciding axial relation therewith. 95

6. In telephonic apparatus, a magnetic coil, an armature, and means carried by the armature wholly enclosed within said coil for supporting the armature in resiliently balanced suspension in normal coinciding axial relation with the coil. 100

7. In telephonic apparatus, a permanent magnet having opposed pole pieces, a translating coil, an armature extending between the magnet pole pieces, a diaphragm, vibration transmitting means for said diaphragm having a universal pivotal connection with 105 said armature, and resilient fulcrum means constituting the sole support for the armature and acting to automatically maintain the same in balanced suspension in coinciding axial relation with the coil in its normal position between the magnet poles. 110

8. In telephonic apparatus, a permanent magnet having opposed pole pieces, a translating coil, an armature extending through said coil and projecting between the magnet pole pieces, a diaphragm, a vibration transmitting member connected at one of its ends to the diaphragm and having a universal pivotal connection at its other end with said armature, and resilient fulcrum means for the armature wholly contained within the coil and acting to automatically maintain said armature in balanced suspension in coinciding axial relation to the coil. 115

9. In telephonic apparatus, a cylindrical 120

- magnet coil and its spool, an armature adapted to be positioned through the bore of the coil spool, and means for maintaining the armature in resiliently balanced suspension in coinciding axial relation with the spool bore, said means including parts frictionally engaged with the wall of the spool bore and parts fixed to the armature and resiliently movable with respect to said first named parts. 10. In telephonic apparatus, a magnet coil and its spool, an armature adapted to be positioned through the bore of said spool, and a fulcrum member for the armature including a part surrounding the armature and frictionally engaged with the wall of the spool bore and a relatively movable part fixed to the armature and supporting the same in balanced suspension in normal coinciding axial relation with the bore of the coil spool. 11. In telephonic apparatus, a cylindrical magnet and its spool, a cylindrical armature adapted to be positioned through the spool bore, and a fulcrum member carried by said armature to extend within the spool bore and frictionally coat with the wall thereof, said member having a resiliently movable part fixed to the armature to yieldingly maintain the armature in balanced suspension in normal coinciding axial relation with the bore of the coil spool. 12. In telephonic apparatus, a permanent magnet having opposed pole shoes, a translating coil, a cylindrical armature, fulcrum means supporting the armature in balanced suspension between the opposed ends of the pole shoes, and the end faces of said pole shoes being concaved in eccentric relation to the peripheral face of the armature. 13. In telephonic apparatus, a permanent magnet having opposed pole shoes, a translating coil, a cylindrical armature, fulcrum means supporting the armature in balanced suspension between the opposed ends of the pole shoes, the end faces of said opposed shoes being eccentrically concaved with respect to the peripheral surface of the armature and having their opposite extremities disposed in closer proximate relation to the surface of the armature than the intermediate portions of said concave faces. 14. An armature for magnet telephones, and a cylindrical fulcrum member for the armature, said armature and the fulcrum member having coacting parts detachably securing the fulcrum member in fixed coaxial relation to the armature whereby said armature and the fulcrum member are combined in a single unit for insertion within a coil bore in operative relation to the telephone magnet. 15. In a magnetic structure, an armature consisting of separable parts having complementary means whereby they may be connected or disconnected, and a fulcrum member for the armature having a portion adapted to be interposed between the armature parts and adapted to be engaged by the latter when said parts are connected to secure the fulcrum member in fixed relation to the armature whereby the armature and its fulcrum are combined in a single unit. 16. In a magnetic structure, an armature consisting of two separable parts provided at one of their ends with coacting coupling means, and a fulcrum member for the armature having a portion adapted to be interposed between the opposed ends of the armature parts and upon the coupling means of one of said parts whereby said portion of the fulcrum member is immovably fixed between the armature sections when the latter are connected. 17. In a magnetic structure, a cylindrical armature adapted to be inserted through the cylindrical bore of the coil spool, said armature consisting of two separable parts having connecting means and a fulcrum member for the armature having a portion adapted to be interposed between the armature parts to be engaged and fixedly held thereby when the armature parts are connected, said member being further provided with a contractible part surrounding the armature and adapted for frictional bearing contact with the wall of the coil spool. 18. In a magnetic structure, a cylindrical armature adapted to be inserted through the bore of a magnet coil spool, said armature consisting of two separable parts, and a resilient sheet metal fulcrum member for the armature having a contractible sleeve to frictionally engage the wall of the coil spool and a resiliently yieldable part in spaced relation to one end of said sleeve adapted to be interposed between the armature parts and constituting a yieldable support for the armature to maintain the latter in balanced suspension within the spool bore. 19. In a magnetic structure, an armature consisting of separable parts having complementary coupling means at one of their ends, and a pair of fulcrum members each provided with a part adapted to be interposed between the armature parts and engaged upon the coupling means of one of said parts and associated in fixed relation with the armature when the parts thereof are connected. 20. In a magnetic structure, a cylindrical armature adapted to be inserted through the bore of the magnet coil spool, said armature consisting of separable parts having complementary coupling means at one of their ends, said end portions of the armature parts being externally reduced in diameter, and a pair of fulcrum members each having a split contractible sleeve to surround the reduced portion of one of the armature parts.

- parts and each fulcrum member being also provided with a resiliently movable armature supporting part in spaced relation to one end of the sleeve, said supporting parts 5 of the fulcrum members adapted to be interposed between the parts of the armature to be engaged and held in fixed relation therewith when the armature parts are connected whereby said armature and the fulcrum 10 members are combined in the form of a single unit.
21. An armature for magnet telephones, and a fulcrum member fixed to the armature and for insertion as a unit with the armature 15 within the bore of a magnet coil, said member having a part to coat with the surface of said bore and removably support the armature in operative relation to the magnet.
- 20 22. An armature for magnet telephones and a fulcrum member fixed to the armature for insertion as a unit therewith within the bore of a magnet coil, said member having a part engaging the wall of the coil bore 25 with a resilient frictional pressure to detachably retain the armature in operative relation to the magnet.
23. An armature for magnet telephones and a fulcrum member for said armature insertable as a unit therewith within the bore 30 of the magnet coil, said member having a part fixed to the armature and a second part surrounding the armature in spaced relation to said first named part and frictionally coacting with the wall of the coil bore to 35 detachably retain the armature in its operative position.

In testimony that I claim the foregoing as my invention, I have signed my name hereunder.

LAMBERT SCHMIDT.
